METHOD FOR MAKING REFLEX COPIES

Lodewijk Pieter Frans van der Grinten, Venlo, Netherlands, assignor to Naamlooze Venootschap Chemische Fabriek L. van der Grinten, Venlo, Netherlands, a limited-liability company of Netherlands

Application December 17, 1934, Serial No. 757,933
In the Netherlands December 19, 1933

12 Claims. (Cl. 95—5)

It is known to make reflex copies by a method comprising the steps of applying on an original a sheet containing a layer of bromic silver emulsion subjecting the original to a radiation through 5 said sheet and subdividing said radiation before it passes through the layer of sensitive material into small areas of lower and higher photochemical power. This method, however, does not give good reflex copies.

10 Now it has been found that good reflex copies can be obtained by other methods to be further described, whilst the type of the rays employed may be also of importance.

If one compares with the help of the microscope 15 those parts of the reflex copy that were during the production of the latter over the dark regions of the original, with the employed subdivision into regions of greater and of smaller actinic intensity, consequently for example with the employed 20 screening, there will be found that a considerable action on the sensitive layer in the portions of smaller photochemical action has occurred. The result of this action is hereinafter called the "halo"; it may for example be practically expressed by the reduction of the covering factor 25 of the screening of the portions in question (the covering factor being the surface of the regions of smaller photochemical action, or the corresponding regions in the reflex copy, per unit of 30 surface).

Now it has been found that the halo exerts a large injurious influence on the strength of the picture. The object of the present invention is therefore "to limit this halo". Wherever herein-after reference is made to rays, or to transparency or to capacity of reflexion therefore, this 35 always means that reference is made to rays of such wave lengths as influence photochemically the sensitive layer or layers employed.

40 The requirements necessary for the practical avoidance of a halo in the sensitive sheet are dependent on many different factors, likewise the importance of the halo itself. They are determined inter alia by the kind and the coarseness 45 of the subdivision into regions of greater and of smaller actinic intensity which has been employed by the picture- or image-distance (distance in mm. between the layer in which the picture is produced and the original) in relation 50 thereto, by the nature of the original, and the like. The present invention, however, is not concerned with these factors but only with the effect on the halo for so far as it is dependent on the nature of the sensitive layers employed and 55 the diffusion of the rays by these layers.

In order to diminish the halo it is required to avoid a diffused radiation into the areas of smaller actinic intensity. It has been found that one necessary condition to obtain this is the use of a sensitive layer, which—at least during a considerable part of the necessary irradiation—has a high coefficient of directed propagation for the rays by which the image is formed.

The expression "coefficient of directed propagation" of a sensitive layer for definite rays is 10 defined as the reversed ratio between the actinic intensity of a small band (the smallest dimension of which should not exceed the thickness of the layer) of parallel rays of the kind employed as it is measured when perpendicularly impinging 15 upon the front surface of the sensitive layer and the actinic intensity of this band of rays after passing through the sensitive layer as it is measured in the area which is the perpendicular projection of the area of the front surface upon 20 which said band impinges on the back surface of 25 said layer.

There are several sensitive layers capable of complying with the above mentioned requirements owing to the nature of their sensitive material.

In some cases the effect of a high coefficient of directed propagation on the halo may still be improved by direct reduction of the unavoidable diffusion of radiation in the sensitive layer. Such 30 diffusion may occur even in sensitive layers of high transparency and fairly high coefficient of directed propagation and may be limited for instance by the use of finely grained or soluble sensitive materials.

In the choice of the sensitive sheet there must further be taken into account for example the quantity of sensitive material present and its distribution in the sensitive sheet. For this reason, for the purpose of reducing the halo it 40 is advantageous to have the quantity of the sensitive material as small as possible, which will in many cases present at the same time the advantage that smaller quantities of the radiation suffice for the production of the reflex copy. The 45 picture production is of course determined simply by the reflected radiation and this radiation is only small owing to the restricted capacity for reflexion of the originals that occur in practice and, in the case of covering screening, of the restricted amount of the radiation energy passing into the system, so that for these reasons already the operation is uneconomical as regards the useful effect of the radiation. Of course, with a 50 layer containing less sensitive material, for in- 55

stance a thin layer, there is obtained also a smaller picture strength, which, however, may be increased by recopying. Where hereinafter it is a question of "strong reflex copies" there are 5 meant thereby copies that are strong in relation to the layer employed in the making of them.

In all these cases an improvement is obtained by using a sensitive layer, which—at least during a considerable part of the necessary irradiation 10 by said rays—has not only a high coefficient of directed propagation but in which also the ratio between the amount of radiation diffused into the sensitive layer and the radiation leaving the sensitive layer in the direction of the original is 15 small.

If dispersion should not be avoided completely it should be caused to take place during the production of the reflex copy merely in the space located between the sensitive layer or the sensitive 20 layers, and the original.

A special selection of the rays to be employed is of course of importance merely for layers that are sensitive over a comparatively wide range of wave lengths. Within such a range the transparency and the ray dispersion may vary with 25 the wave length. In such a case there are preferably chosen, in as far as the selectively reflecting properties of the original allow of this in the sense of what has been said, those wave lengths 30 for which the transparency is the greatest and the ray dispersion is the smallest. As an example for this there may be mentioned the employment of a yellow filter.

It may be here mentioned that in the case of 35 comparative tests for determining an effect according to the invention all the factors that can affect the magnitude and the importance of the halo, other than the nature of the sensitive layers, as, inter alia, the above mentioned factors, must 40 remain constant and only the nature of the sensitive layer with respect to the rays employed should vary.

It is also to be assumed and taken for granted 45 that the sensitive layers work contrasting to a reasonable extent.

It has further been found that it is not necessary that a high coefficient of directed propagation exists in the sensitive layer already in the beginning of the process for making the reflex 50 copy. There are sensitive materials which are decomposed by the radiation into substances having a much increased transparency for such rays. In that case the coefficient of directed propagation increases by the initial irradiation to a maximum when all the sensitive material in the 55 regions of greater actinic intensity has been decomposed. Such layers generally absorb the radiation until they are completely decomposed but do not diffuse the radiation or only to a very 60 small extent. This makes these layers very suitable for the purpose of the present invention. Examples of such layers are cyanotype layers, layers containing a sensitive iron salt which can be developed by means of gallic acid and chromate 65 layers that bleach to a colourless substance.

The following examples serve to illustrate the invention which is by no way limited thereto. The examples will be described in connection with the accompanying diagrammatic drawing which shows in cross section a covering screen, a sensitive 70 sheet and part of an original.

Example 1

An original O (see figure) which consists of a 75 sheet of clear-white paper printed on both sides

with black printing, is placed with the side upward from which it is desired to make a reflex copy. On this there is placed with upwardly turned emulsion layer, a celluloid sheet (DR) 0.1 mm. thick, which is provided with a normal 5 silver halide gelatine layer (GL), 0.01 mm. thick, and thereon a lined covering screen (R) (made in a thin layer of silver applied on a glass plate) with a coarseness of 0.14 (width of the covering lines in mm.) a distance between the covering 10 lines of 0.03 mm., consequently a period of 0.17 mm. and a covering factor of 0.82 (the ratio of the covered surface to the total surface).

The whole is well pressed together in a pressure frame so that an adequate contact is produced 15 between the original, the sensitive layer, and the screen.

Irradiation is effected through a yellow filter by means of an electric incandescent lamp of 100 watts at a distance of 40 cm. in the middle in front 20 of the system so that the rays impinge first upon the screen, then upon the sensitive layer, and finally upon the original.

After adequate irradiation, development takes 25 place and fixing is effected in an ordinary manner. There is obtained a negative reflex copy in the transparent portions of which (these are consequently the portions that in the making of the reflex copy were laid over the black part of the original Z, indicated in the drawing by hatching 30 in O) the coarseness (by which is meant here the width of the transparent lines that correspond in each case to the covering lines of the screen) is reduced from 0.14 to 0.10, and the covering factor 35 (here consequently the ratio of the transparent surface to the total surface, measured between the limits of the transparent portions) is consequently reduced from 0.82 to 0.59, so that there has occurred a halo of 0.23.

If, instead of working according to the method 40 in which the above mentioned emulsion is employed, there is employed a grainless so-called Lippmann emulsion, which is clear, the halo is too 45 small to be measured. The coarseness in the transparent portions is then exactly 0.14. In the case of the employment of this emulsion there may be also employed white light (sunlight, incandescent lamp without yellow filter). There is then obtained in the pervious portions of the negative reflex copy a coarseness of 0.13, corresponding to a covering factor of 0.76 and consequently a halo of 0.82—0.76=0.06.

In the case of the employment of normal 55 Kodak film there would be obtained for example a coarseness of 0.09, i. e. a halo of 0.29, which is so great that the reflex copy is hardly better than the one obtainable with the same film in the old way without any screen.

Of course all the measurements were made under exactly like conditions so that the results 60 were comparable.

Example 2

An original, a sensitive sheet, and a screen 65 were arranged in the manner stated in Example 1. In order to render comparison possible, all the conditions were made as much as possible the same as stated in Example 1. (See the drawing.) As a sensitive layer there is employed a blue-print or cyanotype layer, which is applied to the front side of an acetylcellulose sheet 0.10 mm. thick, which had on this side 70 been made hydrophilic to a depth of 0.02 mm., 75

for example by saponification. The sensitive solution employed consists of

- 10 parts by weight of green ferric ammonium citrate
 5 1 part by weight of potassium ferric cyanide, and
 20 parts by volume of water.

The rear side of this sheet is matted that is 10 to say rendered dull for the purpose of increasing the legibility of the reflex copy to be made.

This layer has when unirradiated little transparency to the chemically active rays; during 15 the irradiation this transparency continuously increases and has become comparatively great when the irradiation is finished, and the layer has obtained a high coefficient for directed propagation.

An arc lamp at a distance of 40 cm. serves as 20 the source of radiation.

After completion of the irradiation the sensitive sheet is measured microscopically. The colourless portions have a coarseness of 0.12 and consequently a halo of 0.12. Washing is now 25 effected in a dilute potassium ferric cyanide solution and then in water.

A strong negative reflex copy is obtained.

If the rear side of the sheet is not matted there is a coarseness of 0.14 and consequently 30 no halo.

Example 3

The operation is exactly like in Example 2 (see the drawing). The sensitive sheet consists 35 of a celluloid sheet 0.10 mm. thick, which is provided with a gelatine sensitive iron salt layer 0.01 mm. thick, which was prepared with a solution of

Percent

- 40 Ferric sulphate ----- 5
 Ferric chloride ----- 3
 Tartaric acid ----- 5

This layer has, when unirradiated, a small, but 45 after irradiation, a large transparency to chemically active rays, and then a high coefficient of direct propagation.

After the completion of the irradiation the sensitive sheet is measured microscopically. There is found to be a coarseness of 0.14 in the 50 covering portions and consequently no halo.

Developing then takes place in a solution of

Percent

- 55 Gallic acid ----- 0.7
 Oxalic acid ----- 0.1

and then immersion in a strong formaline bath.

There is obtained a strong positive reflex copy. When there is employed a lens covering screen the irradiation times are reduced.

60

Example 4

For the purpose of enabling comparison to be made, the operation again takes place in the manner stated in the foregoing examples (see the 65 drawing).

A sensitive bleaching chromate layer is produced by impregnating on its saponified side a unilaterally saponified acetylcellulose sheet with a solution of

Parts by weight

- 70 Bichromate of potassium ----- 1
 Phosphoric acid, sp. gr. 1.32 ----- 3
 Water ----- 2

75 This layer is yellow coloured and becomes on

irradiation practically colourless. Consequently its transparency to rays at the conclusion of the irradiation is great in the regions of greater photochemical activity, after the completion of the irradiation development takes place for instance in aniline vapour or in a solution of aniline in dilute hydrochloric acid. There is obtained a positive reflex copy the covering portions of which have a coarseness of approximately 0.13 so that there is consequently a 10 hardly noticeable halo of less than 0.06.

What I claim is:—

1. A process for making reflex copies comprising the steps of applying on an original a sheet containing a sensitive layer of the type which exhibits a high coefficient of directed propagation for the rays by which the image is formed for at least a considerable part of the required irradiation, said layer being selected from the group consisting of Lippmann emulsion layer, 15 cyanotype layer, sensitive iron salt layer, bleaching chromate layer, subjecting the original to a radiation through said sheet, and subdividing said radiation before it has passed through said layer into small areas of lower and higher photo- 20 chemical power.

2. A process for making reflex copies comprising the steps of applying on an original a sheet containing a sensitive layer of the type which exhibits a high coefficient of directed propagation for the rays by which the image is formed for at least a considerable part of the required irradiation, said layer being a Lippmann emulsion layer, subjecting the original to a radiation through said sheet, and subdividing said radiation before it has passed through said layer into small areas of lower and higher photochemical power. 30

3. A process for making reflex copies comprising the steps of applying on an original a sheet 40 containing a sensitive layer of the type which exhibits a high coefficient of directed propagation for the rays by which the image is formed for at least a considerable part of the required irradiation, said layer being a cyanotype layer, 45 subjecting the original to a radiation through said sheet, and subdividing said radiation before it has passed through said layer into small areas of lower and higher photochemical power.

4. A process for making reflex copies comprising the steps of applying on an original a sheet containing a sensitive layer of the type which exhibits a high coefficient of directed propagation for the rays by which the image is formed for at least a considerable part of the required irradiation, said layer being a bleaching chromate layer, subjecting the original to a radiation through said sheet, and subdividing said radiation before it has passed through said layer into small areas of lower and higher photochemical power. 50

5. A process for making reflex copies comprising the steps of applying on an original a sheet containing a sensitive layer of the type which exhibits a high coefficient of directed propagation for the rays by which the image is formed for at least a considerable part of the required irradiation, said layer being selected from the group consisting of Lippmann emulsion layer, cyanotype layer, sensitive iron salt layer, bleaching chromate layer, subjecting the original to a radiation through said sheet, and subdividing said radiation by the application of a screen before it passes through said layer into small areas of lower and higher photochemical power. 65

6. A process for making reflex copies comprising the steps of applying on an original a sheet containing a sensitive layer of the type which exhibits a high coefficient of directed propagation for the rays by which the image is formed for at least a considerable part of the required irradiation, said layer being a Lippmann emulsion layer, subjecting the original to a radiation through said sheet, and subdividing said radiation by the application of a screen before it passes through said layer into small areas of lower and higher photochemical power.
7. A process for making reflex copies comprising the steps of applying on an original a sheet containing a sensitive layer of the type which exhibits a high coefficient of directed propagation for the rays by which the image is formed for at least a considerable part of the required irradiation, said layer being a cyanotype layer, subjecting the original to a radiation through said sheet, and subdividing said radiation by the application of a screen before it passes through said layer into small areas of lower and higher photochemical power.
8. A process for making reflex copies comprising the steps of applying on an original a sheet containing a sensitive layer of the type which exhibits a high coefficient of directed propagation for the rays by which the image is formed for at least a considerable part of the required irradiation, said layer being a bleaching chromate layer, subjecting the original to a radiation through said sheet, and subdividing said radiation by the application of a screen before it passes through said layer into small areas of lower and higher photochemical power.
9. A process for making reflex copies comprising the steps of applying on an original a sheet containing a sensitive layer of the type which exhibits a high coefficient of directed propagation for the rays by which the image is formed for at least a considerable part of the required irradiation, said layer being selected from the group consisting of Lippmann emulsion layer, cyanotype layer, sensitive iron salt layer, bleaching chromate layer, subjecting the original to a radiation through said sheet, and subdividing said radiation before it has passed through said

layer into small areas of lower and higher photochemical power, said sheet being diffusing only in the space between the sensitive layer and the original.

10. A process for making reflex copies comprising the steps of applying on an original a sheet containing a sensitive layer of the type which exhibits a high coefficient of directed propagation for the rays by which the image is formed for at least a considerable part of the required irradiation, said layer being a Lippmann emulsion layer, subjecting the original to a radiation through said sheet, and subdividing said radiation before it has passed through said layer into small areas of lower and higher photochemical power, said sheet being diffusing only in the space between the sensitive layer and the original.

11. A process for making reflex copies comprising the steps of applying on an original a sheet containing a sensitive layer of the type which exhibits a high coefficient of directed propagation for the rays by which the image is formed for at least a considerable part of the required irradiation, said layer being a cyanotype layer, subjecting the original to a radiation through said sheet, and subdividing said radiation before it has passed through said layer into small areas of lower and higher photochemical power, said sheet being diffusing only in the space between the sensitive layer and the original.

12. A process for making reflex copies comprising the steps of applying on an original a sheet containing a sensitive layer of the type which exhibits a high coefficient of directed propagation for the rays by which the image is formed for at least a considerable part of the required irradiation, said layer being a bleaching chromate layer, subjecting the original to a radiation through said sheet, and subdividing said radiation before it has passed through said layer into small areas of lower and higher photochemical power, said sheet being diffusing only in the space between the sensitive layer and the original.

LODEWIJK PIETER FRANS
VAN DER GRINTEN.
